DESIGN FOR A JACKET OR SIMILAR ARTICLE

Jacob Sniderman, Toronto, Ontario, Canada

Application October 9, 1941, Serial No. 103,698
In Canada August 12, 1941

Term of patent 7 years

To all whom it may concern:

Be it known that I, Jacob Sniderman, a subject of the King of Great Britain, residing at 129 Spadina Avenue, in the city of Toronto, Province of Ontario, Dominion of Canada, have invented a new, original, and ornamental Design for a Jacket or Similar Article, of which the following is a specification, reference being had to the accompanying drawing, forming part thereof.

In the drawing,

Fig. 1 is a front view of a jacket showing my new design, and

Fig. 2 is a side view of the jacket shown in Fig. 1, the sleeve being broken away to more fully illustrate the shirring at the waistline.

The back of the jacket is shirred like the sides at the waistline and is otherwise conventionally plain.

I claim:

The ornamental design for a jacket or similar article, substantially as shown and described.

JACOB SNIDERMAN.
